Primary Examiner — Kevin K Rudzinski*Assistant Examiner* — Woosuk K Shin(74) Attorney, Agent, or Firm — Goldstein Law Offices, P.C.(57) CLAIM

The ornamental design for a half sleeve shirt, as shown and described.

DESCRIPTION

FIG. 1 is a perspective view of a half sleeve shirt in accordance with the present invention;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan elevation view thereof; and,

FIG. 8 is a perspective view of the half sleeve shirt donned on an individual.

The broken lines showing of human arms in FIG. 8 is for the purpose of illustrating environmental structure that form no part of the claimed design.

The broken lines within the openings of the shirt shown in the figures depict boundary lines and form no part of the claimed design.

1 Claim, 6 Drawing Sheets(56)
